(57) **CLAIM**

The ornamental design for a box kite eye socket and plug combination, as shown and described.

DESCRIPTION

The present application is related to U.S. patent application Ser. No. 29/611,370 file on Jul. 20, 2017 for a Box Kite Strut Connector, which is incorporated herein by reference in its entirety.

FIG. 1 is a top perspective view of a box kite eye socket and plug combination showing my new design;

FIG. 2 is a bottom perspective view thereof;

FIG. 3 is a top view thereof;

FIG. 4 is a side view thereof;

FIG. 5 is a view from the left end thereof;

FIG. 6 is a view from the right end thereof;

FIG. 7 is a top perspective view of the box kite eye socket and plug combination showing the eye socket disconnected from the plug for purposes of disclosure;

FIG. 8 is a top perspective view of the eye socket;

FIG. 9 is a bottom perspective view of the eye socket;

FIG. 10 is a top view of the eye socket;

FIG. 11 is a side view of the eye socket;

FIG. 12 is a view from the left end of the eye socket;

FIG. 13 is a view from the right end of the eye socket;

FIG. 14 is a top perspective view of the plug;

FIG. 15 is a bottom perspective view of the plug;

FIG. 16 is a left side view of the plug;

FIG. 17 is a right side view of the plug;

FIG. 18 is a top view of the plug;

FIG. 19 is a bottom view of the plug;

FIG. 20 is a view from the right end of the plug; and,

FIG. 21 is a view from the left end of the plug.

The broken lines in the drawings depict portions of the box kite eye socket and plug combination that form no part of the claimed design.
